UNITED STATES PATENT OFFICE

JAMES E. NEWTON, OF CANTON, OHIO, ASSIGNOR TO CENTRAL ALLOY STEEL CORPORATION, OF MASSILLON, OHIO, A CORPORATION OF NEW YORK

APPARATUS FOR OPENING TAP HOLES OF OPEN-HEARTH FURNACES AND THE LIKE

Continuation of application Serial No. 245,617, filed January 9, 1928. This application filed November 5, 1928. Serial No. 317,388.

This invention relates to apparatus for opening tap holes of open hearth furnaces and the like, and is a continuation of my application Serial No. 245,617, filed January 9, 5 1928.

An object of the invention is the provision of apparatus for opening tap holes of open hearth furnaces and the like, which will effectively prevent injury to the operator's person 10 and/or damage to his clothes.

Another object of the invention is the provision of apparatus for opening tap holes of open hearth furnaces and the like, the various parts of which are readily and easily detachable from each other, and in which a defective or worn out part can be quickly and inexpensively replaced without material loss of time.

These and other objects of the invention will become more readily apparent in the 20 course of the following description of a preferred embodiment of the invention, taken in connection with the accompanying drawings, wherein

Fig. 1 is a perspective view showing the 25 apparatus of the present invention connected to a tank containing oxygen under pressure, and showing also the manner in which the novel apparatus is held by an operator when it is employed to open a "frozen" tap hole of 30 an open hearth furnace or the like;

Fig. 2 is a view, partly in elevation and partly in section, through the apparatus.

Referring more particularly to the drawings, the apparatus includes an operating 35 handle or shield 1, interiorly threaded at one end for the reception of a connector 2 and a circular lock nut 3. In the use of the apparatus, this handle, which is approximately thirty inches long, and about one and one-quarter inches in diameter, is adapted to be 40 grasped by the operator, as shown in Fig. 1. The connector 2 has oppositely extending reduced threaded portions 4 and 5, and has extending therethrough, a bore 6. The lock 45 nut 3 is of considerably greater diameter than the handle 1, and has an exteriorly threaded reduced portion 7.

Secured to the threaded portion 5 of the connector 2 is an interiorly threaded coupling 50 8, and secured to the opposite end of this cou-

pling is a burner pipe 9 having a bore 10 therein which communicates with the bore 6 in the connector 2. A collar 11 is employed as a spacer between the connector 2 and the lock nut 3.

The reduced end portion 4 of the connector 2 has secured thereto a rubber tube 12 of considerable length, and this tube is in turn secured to the valve 13 of a tank 14 containing oxygen under pressure.

On an open hearth furnace or the like, the tap hole, after the pouring operation, ordinarily becomes filled up with metal which solidifies, and in preparing the furnace for the succeeding heat, it is necessary to remove 60 this "frozen metal."

Hitherto it has been customary to melt the metal out of the tap hole by the use of oxygen, and for this purpose, a piece of rubber tubing, such as 12, having one end connected to an oxygen tank, and its other end directly connected to a burner pipe, such as 9, is ordinarily employed. The burner pipe, which is about nine or ten feet long is grasped by the operator at or near the junction of the pipe and tubing, and this junction of the pipe and tubing is held very close to the body of the operator. The end of the burner pipe is held in close proximity to the hot mass of metal in the tap hole, and the metal is rapidly 70 burned and melted away by the oxygen. The oxygen, being under fairly high pressure, causes the molten metal in the tap hole to be scattered about in the form of small incandescent particles, commonly called "sparks," 75 and many of these particles settle on the operator's clothes and hands. In the absence of a higher concentration of oxygen than is usually present in the atmosphere, these incandescent particles quickly become cooled 80 and cause no injury to the operator's hands and/or to his clothes. Very often, however, the end of the burner pipe, when held too closely to the mass of metal in the tap hole, becomes welded shut and in such cases, the rubber tubing, owing to the high oxygen pressure, will usually blow off or become loosened 85 at its point of junction with the burner pipe. The escaping oxygen, under these conditions, will prolong the incandescent condition of the 90 95 100

small metallic particles, mentioned above, for a sufficient length of time, to cause severe injury to the operator's hands, or damage to his clothes.

5 In a number of instances, of which I am aware, severe injuries and death have resulted from these occurrences, and the hazard involved makes it difficult at times to secure operators for this type of work.

10 Under like conditions, if there are weak or defective points in either the rubber tubing or in the burner pipe, blowouts are liable to occur at these points, due to the building up of the oxygen pressure, and similar injuries, initiated by the escaping oxygen, likely to occur to the operator.

In cases where the connection of the rubber tubing and burner pipe has become loosened, or where there are pinholes in the rubber tubing or burner pipe, oxygen, escaping through the loose connection, or through the pinholes, will cause trouble, even if the end of the burner pipe does not become welded shut.

Inasmuch as the operator is already at a distance of nine or ten feet from the tap hole, this being considered the minimum safe distance, mere lengthening of the burner pipe to enable the operator to stand further away from the tap hole, while admittedly serving 30 to lessen the operator's hazard, would be impractical, owing to the difficulty the operator would have in effectively directing the jet of oxygen to the desired point.

In the use of the present apparatus if the 35 rubber tube 12 blows off at its point of junction with the connector 2, as the result of the end of the burner pipe 9 becoming welded shut, the end of the rubber tubing will necessarily have to travel backward the entire 40 length of the handle or shield 1, and since the rear end of the handle is normally a considerable distance back of the operator's person, and also removed from the zone of flying 45 incandescent metallic particles, the oxygen will escape from the end of the rubber tubing at a point sufficiently removed from the operator's person to avoid injury to the latter.

Even if the rubber tubing does not blow off, but merely becomes loosened at its point of 50 junction with the connector 2, the oxygen must necessarily escape through the rear open end of the handle 1, which, as stated above, is at a point sufficiently removed from the operator's person to avoid injury to the latter. By thus providing an outlet for escaping oxygen, very little oxygen pressure can be built up in the handle 1, and all danger of bursting of the handle is thereby eliminated.

The lock nut 3 and collar 11 serve to lock 60 the connector 2 in place, and prevent it from working loose. By thus locking the connector 2 securely in place, the burner pipe 9, after it has become shortened to such an extent as to render it unfit for further use, can be 65 quickly and readily unscrewed from coupling

8, and replaced with a new pipe without disturbing the connector.

If desired, the coupling 8 may be made integral with the connector 2, and the lock nut 3 may be made integral with the collar 11, thereby dispensing with the use of the separate collar.

It is to be understood that these changes, as well as others, may be made without departing from the invention, the scope of which is 75 defined in the appended claims.

It will also be understood that the apparatus is not intended to be limited for use in opening tap holes of open hearth furnaces, and the like, but may be used for various other purposes, such as opening "frozen pouring holes" of ladles, in cutting heavy sections of metal, etc.

Claims:

1. Apparatus for opening tap holes of open hearth furnaces and the like, comprising a tube adapted for attachment to an oxygen supply tank, a burner pipe connected to said tube and a shield disposed over the junction of the tube and pipe and serving as a handle to be grasped by the hands of an operator; said shield extending for a considerable distance over the tube and spaced therefrom to provide an open passage, so that oxygen which accidentally escapes from the tube at its junction with the pipe will be discharged from said passage at a point sufficiently removed from the operator's person to avoid combustion of incandescent particles which alight on the operator during the use of the apparatus..

2.. Apparatus for opening tap holes of open hearth furnaces and the like, comprising a shield adapted to serve as a handle to be grasped by the hands of an operator, a connector secured within said shield, a tube secured to said connector and adapted to be attached to an oxygen supply tank, and a burner pipe secured to said connector; said shield extending for a considerable distance over the tube and spaced therefrom to provide an open passage, so that oxygen which accidentally escapes from the tube at its junction with the pipe will be discharged from said passage at a point sufficiently removed from the operator's person to avoid combustion of incandescent particles which alight on the operator during the use of the apparatus.

3. Apparatus for opening tap holes of open hearth furnaces and the like, comprising a shield adapted to serve as a handle to be grasped by the hands of an operator, a connector secured within said shield, a tube secured to said connector and adapted to be attached to an oxygen supply tank, a burner pipe secured to said connector, and a lock nut secured to one end of the shield and serving to retain the connector in the shield; said shield extending for a considerable distance

over the tube and spaced therefrom to provide an open passage, so that oxygen which accidentally escapes from the tube at its junction with the pipe will be discharged from said passage at a point sufficiently removed from the operator's person to avoid combustion of incandescent particles which alight on the operator during the use of the apparatus.

In testimony whereof I affix my signature.
JAMES E. NEWTON.
